UNITED STATES PATENT OFFICE.

FREDERICH DANIEL KEEPS, OF BEATRICE, NEBRASKA, ASSIGNEE TO F. D. KEEPS MFG. CO., OF BEATRICE, NEBRASKA.

DRAFT-DEFLECTOR.

1,359,710.

Specification of Letters Patent. Patented Nov. 23, 1920.

Application filed October 20, 1919. Serial No. 331,902.

To all whom it may concern:

Be it known that I, FREDERICH DANIEL KEEPS, a citizen of the United States, residing at Beatrice, in the county of Gage and State 5 of Nebraska, have invented a new and useful Draft-Deflector, of which the following is a specification.

The present invention relates to draft deflectors, and has as its primary object to 10 provide a deflector for preventing drafts from entering the room but which will not exclude the light from the room.

A further object of the invention is to provide a deflector of this character which 15 embodies transparent panes, a novel and improved mounting being provided for the transparent panes which will retain the same against any vibration whatsoever and which will permit the ready removal of the same.

20 A further object of the invention is to provide a deflector which will exclude drafts from a room and which may be applied to any window without changing the parts thereof.

25 An additional object of the invention is to provide a draft deflector which is simple in construction, which consists of few parts, and which may be manufactured and placed on the market at a minimum cost.

30 With the above and other objects and advantages in mind, the invention consists in the combinations of elements, constructions and arrangements, and general assemblage, the details of which will be hereinafter 35 specifically referred to and defined in the appended claims, one embodiment of the invention being illustrated in the accompanying drawings, wherein:—

Figure 1 is a fragmentary front elevation 40 of a window embodying my improvements; and

Fig. 2 is a vertical sectional view taken on line 2—2 of Fig. 1.

Fig. 3 illustrates a transverse sectional 45 view through the supporting bar and plate.

On the drawing, wherein like characters of reference designate like parts on all of the views, the numeral 5 designates a conventional window construction.

50 Arranged upon the window sill exteriorly of the window is an I-shaped bar 6 which has one end bent laterally to provide a securing latch 7 which is secured to the window sill. This I-shaped member includes a

flat bar of metal and a length of sheet metal, 55 the latter being formed with a longitudinal depression 9 for providing flange 10 forming guides or grooves 10' at the opposite sides of the I-shaped member, which grooves 10' form window supporting elements. 60

As shown, the length of sheet metal 9' is secured to the flat bar 6, through the medium of the screws 6', passing through registering openings formed in the bar 6 and length of sheet metal 9'. 65

End plates 11' are mounted at opposite sides of the window, the I-shaped member being disposed centrally of the end plates and extends vertically and at an angle. The inner ends of these end plates 11' are bent 70 at right-angles as at 11 and secured to the window frame by fastenings 12, passing through the elongated openings 13' formed therein. The forward longitudinal edges of these end plates are bent inwardly and at 75 right-angles and coöperate with the clips 14' stamped from the body of each flange 11', the same being disposed in spaced relation with each other to provide window pane supporting flanges 13, these plates being bent so that these flanges extend at the same angle as the bar 6, from each of the plates and are extended inwardly and arranged parallel with the flanges 11. Transparent panes 15 are engaged in the grooves 80 of the I-shaped bar and between the flanges and the clips on the end plates.

The embodiment of the invention herein shown and described is considered the preferred construction, but it is to be understood that modifications can be made in the invention in many respects and that my limits of such modification are only governed by the appended claims. 90

What is claimed is:—

1. In a draft deflector, a bar having one end bent laterally and secured to the window sill, the bar being disposed at an oblique angle, a plate secured to the bar having a central longitudinal depression whereby 100 grooves are formed at opposite sides of the same, end plates secured to the opposite sides of the window frame and transparent panes engaged in the grooves and engaged by the end plates. 105

2. In a draft deflector, end plates secured to the opposite sides of the window frame having inwardly extending flanges formed

at its longitudinal edges, the flanges being disposed at an oblique angle, an angularly disposed I-shaped bar secured to the sill of the window and disposed centrally between the end plates, transparent panes having their inner edges engaged in the I-shaped bar and their opposite edges supported on the flanges of the end plates, and clips struck from the end plates and overlying

the edges of the panes to prevent the same 10 from moving in one direction.

In testimony that I claim the foregoing as my own, I have hereto affixed my signature in the presence of two witnesses.

FREDERICH DANIEL KEEES.
